UNITED STATES PATENT OFFICE.

NELSON L. JACOBUS, OF HEMPSTEAD, NEW YORK, ASSIGNEE TO THE ELECTRO CHEMICAL ENGRAVING COMPANY, OF BROOKLYN, NEW YORK, A CORPORATION OF NEW YORK.

DESIGN FOR A CALENDAR STAND.

Application filed August 25, 1924. Serial No. 10,543. Term of patent 14 years.

To all whom it may concern:

Be it known that I, NELSON L. JACOBUS, a citizen of the United States, residing in Hempstead, in the county of Nassau and State of New York, have invented a new, original, and ornamental Design for Calendar Stand, of which the following is a specification, reference being had to the accompanying drawing, forming part thereof.

The figure is a perspective view of a calendar stand showing my new design.

I claim:

The ornamental design for a calendar stand, as shown.

Signed at Brooklyn, in the county of Kings and State of New York, this 19th day of August, 1924.

NELSON L. JACOBUS.
